CLAIM

The ornamental design for a stand with display as shown and described.

DESCRIPTION

FIG. 1 is a top front isometric view of a stand with display showing the claimed design;

FIG. 2 is a top rear isometric view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines in the figures show environment and portions of the stand with display that form no part of the claimed design.

1 Claim, 7 Drawing Sheets

Related U.S. Application Data

is a continuation of application No. 29/881,846, filed on Jan. 6, 2023, now Pat. No. Des. 1,036,451.
